Primary Examiner — Wendy L Arminio*Assistant Examiner* — Carrie S Gelula(74) *Attorney, Agent, or Firm* — Perkins IP Law Group LLC; Jefferson Perkins(57) **CLAIM**

I claim the ornamental design for a stand for large handheld electronic device, as shown and described.

DESCRIPTION

FIG. 1 is a top right front perspective view of our design;

FIG. 2 is a front view thereof;

FIG. 3 is a right view thereof;

FIG. 4 is a left view thereof;

FIG. 5 is a rear view thereof;

FIG. 6 is a top view thereof; and,

FIG. 7 is a bottom view thereof.

The bottom of the stand is unadorned and forms no portion of the claimed design. The broken lines shown illustrate environment that forms no part of the claimed design.

1 Claim, 7 Drawing Sheets(56)
